UNITED STATES PATENT OFFICE.

CAMILLE ANTOINE ZACKIEWICH, OF PARIS, FRANCE.

APPARATUS FOR THE CONTROL OF THE LEAVES OF WEAVING LOOMS.

Application filed October 5, 1922. Serial No. 592,609.

To all whom it may concern:

Be it known that I, CAMILLE ANTOINE ZACKIEWICH, a citizen of the Republic of France, and residing at Paris, Seine Department No. 47, Rue d'Hautpoul, in the Republic of France, engineer, have invented certain new and useful Apparatus for the Control of the Leaves of Weaving Looms, of which the following is a specification:

10 My invention relates to an improved apparatus for the control of the leaves of a weaving loom; wherein the known jacquard pattern sheets are replaced by a set of revoluble discs (termed patterns) having disposed at the periphery one or more teeth whose number and spacing are variable for the different discs. When rotating, the teeth of each pattern disc effect the momentary clutching of a respective shaft with one or 20 the other of two driving pinions mounted loose upon said shaft and in constant rotation in contrary sense; the consequent rotation of said shaft serve to raise or lower the corresponding loom leaf through the medium of adequate mechanical devices.

The present improvements chiefly relate to the devices controlled by said pattern discs and serving for the clutching of said leaf-controlling with the driving pinions. 30 These arrangements principally comprise the use of an eccentric provided with a collar for actuating the forked lever of each clutch sleeve, said eccentric being so controlled that it rotates through one half revolution upon the passage of each tooth of the pattern. By these means, the apparatus is easy-running and it takes but a small amount of power.

A form of construction of an apparatus 40 according to the invention is shown by way of example in the accompanying drawings.

Fig. 1 is a partial vertical section of the device, and,

Fig. 2 a horizontal section.

45 Figs. 3 and 4 are front and side elevational views, of a diagrammatic nature, of the device as a whole and of the mechanical transmission for the control of the driving pinions and the patterns.

50 A description will first be given of the drive which relates to a single leaf of the loom.

55 A disc, termed pattern, 1, carrying one or more teeth and turning in co-operation with the main shaft of the loom, actuates an eccentric disc 2 by means of gearing 3, 4, 5, 6,

7 whose ratio is such that disc 2 will turn through one half revolution at each passage of a tooth of the pattern.

The eccentric disc 2 is mounted loose on 60 a shaft 8 and rotates in a collar 9 connected by a rod 10 with a lever 11 pivoted to a stationary shaft 12; said lever actuates by a fork 13 a jaw clutch sleeve of double type 14 which is slidable on a key upon the 65 shaft 15.

By moving the lever 11 and sleeve 14 in one or the other sense, the clutch jaws are actuated by the jaws of one or the other driving pinion 16, 17, which rotate loosely 70 and in contrary sense on the shaft 15; the latter is thus actuated in either sense and drives by means of a worm 18 and worm wheel 19 a pulley 20 to which are secured the drawing bands 21 of one of the loom leaves. 75 As each tooth of the pattern passes along, it thus raises or lowers the corresponding strip. After the passage of the tooth, the eccentric disc as well as the lever 11 and sleeve 14 occupy the inoperative position as indicated in the drawing, this position being maintained for example by a spring 22 slightly braking the pinion 4, Fig. 1.

Each of the shafts 15 serving to actuate the loom leaves is clutched in like manner 85 by a corresponding sleeve operated by an eccentric, a set of gears and a respective pattern.

The apparatus set forth is intended for the control of 24 leaves, and comprises four 90 rows of six shafts each, 15, and two rows of twelve patterns each, 1, for the control of the clutching of said shafts.

The pinions 16 which are mounted on all the shafts 15 of a given row are in engagement in sequence, and the last pinion engages a pinion 23 disposed at the outside of the casing 24 of the apparatus. The pinions 23 are connected together by pinions 25, and one of them is rotated by a chain wheel 26 95 keyed to its shaft, said wheel being connected by chain to a second like wheel mounted on the main shaft of the loom (not shown). In like manner the pinions 17 are in engagement, and the last one engages a 100 pinion 27. The various pinions 27 are connected together by pinions 28, and one of them is rotated in contrary sense to the respective pinion 23 by means of a set of bevel gears 29, 30, 31; the gear 29 is mounted on 105 the shaft 32 of the chain wheel 26; gear 30 is loose on a stationary axle, and gear 31 and

pinion 37 are secured to the same shaft.

The shafts 33 having keyed thereto the pattern disks 1, carry the pinions 34 which are connected together in pairs by a pinion 35, and the latter is driven by a worm 36 whose shaft 37 is connected with the driving shaft 32 through the medium of the bevel gears 38, 39, 40, 41 so that at each revolution of the main shaft of the loom, the patterns will turn through an angle equal to the pitch of their teeth.

The said driving mechanism as a whole occupies but a small space and can be inspected and kept in order with facility.

15 Claims:

1. In an apparatus for the control of the leaves of a loom, the combination of a control shaft for each leaf, a clutch sleeve slideable upon said shaft a forked lever engaging said sleeve, an eccentric disc loosely revolvable upon a stationary axle, an eccentric collar and an eccentric rod connecting said disc with said forked lever, a disc termed "pattern" having one or more teeth and adapted to rotate in co-operation with the main shaft of the loom, and means whereby said eccentric disc may be turned through one-half revolution at the passage of each tooth of said pattern disc.

2. In an apparatus for the control of the leaves of a loom, the combination of a set of parallel shafts, a series of devices actuated by said shafts and adapted to raise and lower the respective leaves of the loom, driving pinions loosely revolvable on one of the said shafts, clutch sleeves mounted on said shafts, a set of toothed discs termed "patterns" shafts having the said patterns keyed thereto, means actuated by the teeth of said discs and serving to move the said sleeves, a driving shaft adapted to rotate in co-operation with the main shaft of the loom, gear wheels connecting said shaft with one-half the said driving pinions mounted on the shafts, other gear wheels connecting said shaft with other driving gear wheels whereby the latter shall be rotated in contrary sense to the preceding, and gear wheels connecting the said driving shaft with the pattern disc shaft whereby each revolution of the driving shaft shall cause the said patterns to move forward by a distance equal to the pitch spacing, substantially as described and represented.

In testimony that I claim the foregoing as my invention, I have signed my name.

CAMILLE ANTOINE ZACKIEWICH.
